CLAIM

The ornamental design for a combined school bus warning light and remote control therefor, as shown and described.

DESCRIPTION

FIG. 1 is a front, top and side perspective view of the combined school bus warning light and remote control therefor embodying the design of the present invention; FIG. 2 is a front elevational view thereof, the rear being a mirror image of the front shown in FIG. 2;

FIG. 3 is a side elevational view thereof, the side opposite being a mirror image of the side shown in FIG. 3; FIG. 4 is a top plan view thereof; and, FIG. 5 is a bottom view thereof.

FIG. 1

FIG. 2

FIG. 4

FIG. 5
